(57) **CLAIM**

The ornamental design for a cat topical dispenser, as shown and described.

DESCRIPTION

The cat topical dispenser is intended for use as a dispenser of a formulation such as a solid, semi-solid or fluid formulation. One example of such a formulation is a formulation intended for tick and flea control on pets, and in particular cats.

FIG. 1 is a perspective view of one embodiment of a cat topical dispenser.

FIG. 2 is a perspective view of another embodiment of a cat topical dispenser.

FIG. 3 is a side view of the cat topical dispenser of FIG. 2; FIG. 4 is a perspective view of the cat topical dispenser of FIG. 2; and,

FIG. 5 is a perspective view of another embodiment of a cat topical dispenser.
